(57) **CLAIM**

The ornamental design for a user interface for a display screen, as shown and described.

DESCRIPTION

FIG. 1 is a front view of a user interface for a display screen showing my new design; and,

FIG. 2 is a front view of a second embodiment of a user interface for a display screen showing my new design.

The broken line showing of the five regions within the claimed area in FIGS. 1 and 2, the indicia in FIG. 2, a device embodying the display screen in FIGS. 1 and 2, and the display screen in FIGS. 1 and 2 is for illustrative purposes only and forms no part of the claimed design.

1 Claim, 2 Drawing Sheets

FIG. 1

FIG. 2
